UNITED STATES PATENT OFFICE.

JAMES IRVING SPENCER, OF CHELSEA, MASSACHUSETTS.

FLY-SCREEN.

SPECIFICATION forming part of Letters Patent No. 293,915, dated February 19, 1884.

Application filed November 15, 1882. (No model.)

To all whom it may concern:

Be it known that I, JAMES IRVING SPENCER, a citizen of the United States, residing at Chelsea, in the county of Suffolk and State of Massachusetts, have invented certain new and useful Improvements in Fly-Screens; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to fly-screens of the sort employing a spring-roller and a sheet or strip of flexible material adapted to be wound automatically thereon; and the said invention consists in a roller having a rabbet, in combination with a flexible extensible screen attached to said roller and having re-enforcing bands or folds, and adapted to be wound thereon, and a longitudinally-slotted cylindrical casing adapted to contain said roller and 25 screen, and having said roller journaled in the ends thereof, said casing and its contents being readily removed from and attached to the wood-work as a single piece.

The drawings accompanying this specification represent, in Figure 1, a view of a window and window-frame with my invention applied thereto. Fig. 2 is a horizontal section of the screen and its roller and containing-case. Fig. 3 is a view of the roller, showing the groove to receive the lap of the screen.

30 In said drawings, A denotes a window-frame, and B the lower sash of a window.

In carrying out my invention I provide a straight tubular case, D, having a longitudinal slot, E, to permit of the passage of the screen. This case contains a roller, F, journaled longitudinally within it, and upon the roller the screen is wound by means of a spring suitably applied, said roller being removable with said 45 case.

G represents a screen in the form of a piece of netting of any suitable material, the inner end of which is secured to the roller F, while its outer end is secured to a strip, H, of wood 50 or other material, containing a ring or catch, I, to engage a stud or fastening secured to the opposite side of the window-frame. The case

D is to be secured in an upright position to one side of the window-frame, as shown, and when it is desired to screen the lower part of the window the netting G is stretched across such window and secured to the opposite side of the window-frame, as shown in Fig. 1. When released, the netting is automatically coiled within said case D by the action of the 55 spring applied to the roller. Under ordinary circumstances the netting G, in the event of a high wind blowing into the window, would be swelled out and separated at top and bottom from the window-sash, thereby permitting of 60 entrance of flies. To avoid this objectionable result, I employ, as one means of effecting the desired result, a narrow band, J, of webbing or other suitable material, which I dispose at the top or bottom, or both, of the netting, and 65 so as to somewhat overlap the latter, as shown in the drawings, the inner end of each band being secured to the roller F, while its outer end is secured to the bar H. As the narrow band J presents small surface to the action of 70 the wind, it remains taut, and by overlapping the edge of the netting prevents distention of such edge; or, in lieu of the independent band J, a longitudinal fold may be taken in one or both edges of the screen, thereby providing a 75 fullness of the screen, to permit the latter to be distended by the wind without separating its edges from the window-sash. The inner edge of the slot in the case D serves to maintain the screen in close contact with the window-sash. It would be possible to dispense 80 with the case D and put the screen-roller F directly to the window or door frame; but in this event the roller must be adapted to approach automatically and recede from such 85 frame as the screen is wound up or unwound, in order to maintain the screen in close contact with such frame.

K in the drawings represents a peripheral groove or rabbet in the roller F, to receive the 90 increased thickness of the screen at the point where the netting and band or the folds of the screen overlap, the object of this being to prevent wrinkling or doubling of the screen at this point, which would otherwise ensue as 95 such screen is rolled up.

In lieu of placing the case D at one side of the window and adapting the screen to be stretched laterally across such window or door,

the case may be located horizontally across the top or bottom of such door or window, and adapted to be raised or lowered with respect to the latter.

- 5 I do not broadly claim a screen attached to a spring-roller which is journaled in a removable case, nor a roller used for such purposes having a rabbet, K, nor a slotted removable cylindrical case for such a roller, being aware 10 that these features are not new; but

What I do claim is—

The roller F, having rabbet K, in combination with a flexible extensible screen attached to said roller, and having re-enforcing

bands or folds J, and adapted to be wound 15 thereon, and a longitudinally-slotted cylindrical casing adapted to contain said roller and screen, and having said roller journaled in the ends thereof, said casing and its contents being readily removed from and attached to 20 the wood-work as a single piece.

In testimony whereof I affix my signature in presence of two witnesses.

JAMES IRVING SPENCER.
